[57] CLAIM

The ornamental design for a jewelry link, as shown and
described.

DESCRIPTION

FIG. 1 is a perspective view of a jewelry link showing
my new design;

FIG. 2 is a top plan view;

FIG. 3 is a side elevational view;

FIG. 4 is a bottom plan view;

FIG. 5 is an end elevational view;

FIG. 6 is an end elevational view opposite the end
shown in FIG. 5;

FIG. 7 is a perspective view of the component in a
position of use; and

FIG. 8 is a perspective view of the component in a
position of use.

The broken line showing of a necklace in FIGS. 7 and
8 is for illustrative purposes only and forms no part of
the claimed design.

FIG. 1
